UNITED STATES PATENT OFFICE.

ATARASHI TANAKA, OF LOS ANGELES, CALIFORNIA.

DISH-WASHER.

1,154,349.

Specification of Letters Patent. Patented Sept. 21, 1915.

Application filed February 8, 1915. Serial No. 6,862.

To all whom it may concern:

Be it known that I, ATARASHI TANAKA, a subject of the Emperor of Japan, residing at Los Angeles, in the county of Los Angeles and State of California, have invented a new and useful Dish-Washer, of which the following is a specification.

My invention relates to dish washers, and the principal object of my invention is to 10 provide a dish washer in which hot or cold water is supplied at will to a brush which does the cleaning.

A further object of the invention is to 15 provide such a brush with means whereby soap can be added to the water if desired and whereby either bar or powdered soap may be used if desired.

Further objects and advantages will be made evident hereinafter. 20 Referring to the drawing which is for illustrative purposes only, Figure 1 is a perspective view of my invention in place in a kitchen sink. Fig. 2 is a partial enlarged section of a portion of my invention. Fig. 25 3 is a perspective view of a brush member, and Fig. 4 is a sectional view of the soap box equipped with a sack for utilizing powdered soap.

In these figures, 11 is a brush member 30 which may be secured in the mouth of a receptacle 12 which is provided with a handle 13 and which is supplied through a flexible hose 14 with hot water from a bib 15 or cold water from a bib 16.

35 The brush 11 consists of a back 17 having a series of perforations 18 formed therein, the perforations being preferably formed between individual bristles 19 secured in the back 17 by any of several well known 40 methods. A grip 20 is formed on the back 17 and a screw thread 21 is also formed thereon, this thread fitting tightly in a similar thread 22 formed in the shell 23 of the receptacle 12. The shell 23 has a projecting spout 24 formed thereon to which is soldered a tube 25 on which the handle 13, which is preferably of wood or other heat insulating material, is placed. The hose 14 is secured over an enlarged end 26 formed 45 on the tube 25. The hose 14 has two branches, one branch 27 connecting to the bib 15 and the other branch 28 connecting to the bib 16.

Located inside the receptacle 12 and turn-

ing freely therein is a soap box 30. This box 55 is preferably formed in two halves 31 and 32, formed of hemi-spherical sheet metal members having a series of holes 33 therein, the halves 31 and 32 being connected by a hinge 34 and locked together by a pin 35 60 and a hasp 36. Small pieces of soap, as shown at 37 may be placed in the box 30, or powdered soap, washing powder, borax, or other chemical substances, as shown at 38, may be placed in a fabric sack 39 having a 65 closure 40 and this sack may be placed in the box 30.

The method of operation of the invention is as follows: The box 30 is filled with soap 37, or the sack 39 is filled with soap 70 powder or the like 38, and the sack 39 is placed in the box 30. The box 30 is then placed in the receptacle 12 and the brush 11 is screwed into place. The branches 27 and 28 are connected to the bibs 15 and 16 and 75 the supply of water flowing through the hose 14 is regulated by these bibs. The water enters the receptacle 12 through the tube 25 impinging diagonally on the box 30 and twisting it in the receptacle 12, so that 80 it rotates, thus constantly presenting fresh surfaces to the water.

The water runs into the bristles 19 through the holes 18. The brush is used to scrub and cleanse all sorts of dishes and cooking utensils, the bristles 19 loosening the grease and dirt which is dissolved by the soapy water. If desired, the brush can be used without soap. In practice several styles of brush 85 can be used with one receptacle. 90

I claim as my invention:—

A dish washer comprising a receptacle, a brush having a perforated back detachably secured in the mouth of said receptacle, a loose spherical box of such a size as to turn 95 freely in said receptacle and to receive soap, and water inlet means for passing water into said receptacle, said water inlet means being so arranged that the entering water turns said box. 100

In testimony whereof, I have hereunto set my hand at Los Angeles, California, this 30th day of January, 1915.

ATARASHI TANAKA.

In presence of—

GEORGE A. LeDOUX,
FORD W. HARRIS.
